DESIGN FOR A CORNER BATHTUB OR THE LIKE

Frank P. Uphues, Chicago, Ill., assignor to Crane
Co., Chicago, Ill., a corporation of Illinois

Application May 6, 1944, Serial No. 113,504

Term of patent 14 years

(Cl. D4—4)

To all whom it may concern:

Be it known that I, Frank P. Uphues, a citizen of the United States, residing at 5933 W. Midway Park, in the county of Cook, city of Chicago, State of Illinois, have invented a new, original, and ornamental Design for a Corner Bathtub or the like, of which the following is a specification, reference being had to the accompanying drawings, forming part thereof.

Fig. 1 is a perspective view of a corner bathtub or the like embodying my new design.

Fig. 2 is a central vertical sectional view.

I claim:

The ornamental design for a corner bathtub or the like, substantially as shown.

FRANK P. UPHUES.
